UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE STRUCTURE.

Application filed June 21, 1924. Serial No. 721,409.

To all whom it may concern:

Be it known that I, HARRY M. PFLAGER, a citizen of the United States, residing at St. Louis, Missouri, have invented a certain 5 new and useful Improvement in Locomotive Structures, of which the following is a specification, such as will enable others skilled in the art to which it appertains to make and use the same.

10 My invention relates to railroad rolling stock and consists in an improved mounting of the locomotive air pump and in a pilot beam adapted for such mounting.

15 The main object of my invention is to move the air pump cylinders as far forward of the locomotive as possible, thereby relieving the drivers of the weight of the air pump and utilizing space which is not required for other purposes.

20 The same general object is attained in the structure illustrated and claimed in my co-pending application, Serial Number 721,408, filed of even date herewith.

25 A particular object of my invention is to seat the air pump cylinders within the pilot beam so as to reduce the space occupied by the assembly and to better protect the pump elements.

30 A further object of my present invention is to carry the air reservoir by the pilot beam and in the preferred form of my invention I adapt the pilot beam to enclose the air reservoir and indeed to form the reservoir.

35 In the accompanying drawings which illustrate a selected embodiment of my invention—

40 Figure 1 is a top view of my improved pilot beam with the air pumps mounted thereon and with the pilot and the adjacent portion of the locomotive frame indicated in dot and dash lines.

45 Figure 2 is a vertical section on line 2—2 of Figure 1.

50 Figure 3 is a front elevation of the parts shown in Figure 2.

The pilot beam 1 is shown as consisting of a one-piece casting, box-shaped in cross section, and adapted to be attached to the front end of the locomotive frame and to have a pilot secured to its forward face.

55 The top wall of the beam is provided with openings near its ends and the rear wall of the pilot beam is bulged outwardly at 2 adjacent the openings all for the purpose of

receiving air pump cylinders 3 in the recess so formed. A vertical bracket 4 extends upwardly from the top of the beam in front of the opening therein and is provided with downwardly and rearwardly inclined reinforcing flanges 5 located at the sides of the opening and forming with the recessed body of the beam a housing substantially enclosing the air pump steam and air cylinders.

60 The rear of the front wall of the beam and of bracket 4 is provided with integral pads 6 and 7, respectively, to which may be bolted the cylinder brackets 8 and 9. Between the pads 6 on the beam body I prefer to provide one or more openings 10 and similar openings 11 may be provided in the rear wall of the beam. These openings permit the circulation of air to and about the cylinder to cool the latter. Openings 12 may be provided in bracket 4 for a similar purpose 65 or to lighten the structure, if desired.

70 It will be understood that the cylinders may be connected with the steam supply and with ordinary air reservoirs by suitable piping. I prefer, however, to construct the 75 pilot beam so that it may serve as the air reservoir or house the latter if desired and in the drawings partitions 13 extend between the front and rear walls and between the top and bottom walls of the beam, thereby forming a rectangular reservoir to which pipes 14 lead from the air cylinders 3 and an outlet pipe 15 leads to the air brake system or other application of the air. Obviously, a separate reservoir could be 80 seated in a suitable recess in the beam similarly to the mounting of cylinders 3 and various other modifications in the details of my invention will suggest themselves to 85 those familiar with the art. I contemplate 90 the inclusion of such modifications within the scope of my invention as claimed.

95 I claim:

1. A locomotive pilot beam provided with a recess adapted to receive a pump cylinder, a cylinder mounting flange on said beam adjacent said recess, said flange and the wall of said recess being perforated to facilitate the circulation of air about an adjacent pump cylinder.

100 2. A locomotive pilot beam provided with a recess adapted to receive a pump cylinder and provided with an opening adjacent said recess to permit the passage of air through the beam to a cylinder mounted therein.

- 2
3. A locomotive pilot beam provided with a recess adapted to receive a pump cylinder, and a shield on said beam extending outwardly from said recess.
- 5 4. A locomotive pilot beam having an upwardly opening recess between its front and rear wall, and integral flanges extending upwardly from the sides of said recess, said recess and flanges being adapted to receive 10 and mount the steam and air cylinders of an air pump.
5. In a locomotive pilot beam, an integral vertical bracket projecting upwardly from the top of the beam near the front thereof, 15 and spaced reinforcing flanges extending rearwardly and downwardly from said bracket to the top of the beam, the top of said beam being recessed between said flanges.
- 20 6. In a locomotive pilot beam, a vertical bracket projecting upwardly from the top of the beam near the front thereof, and spaced reinforcing flanges extending rearwardly and downwardly from said bracket 25 to the top of the beam, the top of said beam being recessed between said flanges and the front of said beam being apertured below said bracket to provide an air passage to said recess.
- 30 7. In combination, a pilot beam provided with a recess, a projecting flange on said beam adjacent said recess, and a pump seated in said recess with its projecting portions shielded by said recess flange.
- 35 8. A locomotive pilot beam having a recess to receive a fluid pump and provided with a fluid reservoir adjacent to said recess.
9. A locomotive pilot beam having a recess to receive a fluid pump and enclosing a fluid reservoir adjacent to said recess.
- 40 10. A locomotive pilot beam having recesses near its ends to receive fluid pumps and forming a fluid reservoir between its recessed portions.
- 45 11. A locomotive pilot beam of box-shaped cross section provided with a lateral bulge intermediate its ends, the top wall of said beam having an opening adjacent to
- said bulge, and upstanding brackets on said beam surrounding said opening. 50
12. A locomotive pilot beam of box-shaped cross section, the rear wall of which is provided with an outwardly bulged portion, the upper wall of the beam having an opening adjacent to said portion, and integral upstanding brackets on said upper wall surrounding said opening. 55
13. In combination, a pilot beam provided with a recess, a shield on said beam extending outwardly from said recess, and a pump mounted on said shield and extending into said recess. 60
14. In combination, a pilot beam provided with a recess, a shield on said beam extending outwardly from said recess, and a pump secured to said beam and shield and extending into said recess. 65
15. In combination, a pilot beam provided with a recess, a shield on said beam extending outwardly from said recess, and a pump mounted on said shield and extending into said recess, said beam being apertured adjacent to said pump to admit air to the same. 70
16. In combination, a pilot beam having a hollow portion forming a fluid reservoir and having a recessed portion adjacent thereto, and a fluid pump mounted in said recessed portion and connected to said reservoir. 75
17. In combination, a pilot beam having a hollow portion forming a fluid reservoir and having recessed portions adjacent each end thereof, and fluid pumps mounted in said recessed portions and connected to said reservoir. 80
18. In combination, a pilot beam of box-shaped cross section, the rear wall of which is provided with an outwardly bulged portion, the top wall of said beam having an opening adjacent to said portion, upstanding brackets on said upper wall surrounding said opening, and an air pump substantially enclosed by said portion and brackets. 85
- In testimony whereof I hereunto affix my signature this 28th day of May, 1924.
- H. M. PFLAGER.
